UNITED STATES PATENT OFFICE.

GEORGE E. EVANS, OF WACO, TEXAS.

COTTON GIN.

Original application filed March 13, 1922, Serial No. 543,253. Divided and this application filed February 26, 1923. Serial No. 621,442.

To all whom it may concern:

Be it known that I, GEORGE E. EVANS, citizen of the United States of America, residing at Waco, in the county of McLennan and State of Texas, have invented certain new and useful Improvements in Cotton Gins, of which the following is a specification.

This invention relates to new and useful 10 improvements in air blast gins.

In gins of this type lint cotton and bits of leaves, seed hulls and other trash known as "motes" are carried through the saw spaces between the ribs from the roll box. 15 The lint cotton is removed by air nozzles and deflected into a cotton flue from the saws, while the motes are thrown off and collected in a conveyer trough. The mouth of the nozzle is generally located at a point 20 best suited to remove the lint and centrifugal force or gravity is relied upon to take care of the motes. With the best of engineering skill no flue has yet been designed which will not take more or less motes into 25 its mouth. Motes in the lint cotton which reaches the condenser is undesirable and if eliminated, a higher grade of cotton would be produced.

The object of the invention is to so locate 30 the mouth of the air flue as to not only give the saws a full opportunity to cast off their motes, but to prevent trash and other foreign matter from falling into the mouth of the flue.

35 A further object is to provide a gin structure in which the peripheries of the saws are free from obstructions from the point where they pass between the ribs to the mouth of the air flue.

40 Another object of the invention is to amplify the peripheral distance from the point where the saws pass between the ribs to the mouth of the air flue, thus giving the saws a greater opportunity to demote. By 45 means of this amplified spacing it is possible to run the saws at a comparatively slow speed, whereby moting is more efficiently carried out and a cleaner staple is produced. This is desirable even though it reduces the 50 capacity of the gin.

A construction designed to carry out the invention together with other features will be hereinafter described.

55 The invention will be more readily understood from a reading of the following speci-

fication and by reference to the accompanying drawings, in which an example of the invention is shown and wherein:

Fig. 1 is a vertical sectional view of a gin constructed in accordance with my invention, and

Fig. 2 is a similar view of a modified form.

In the drawings the numeral 10 designates an ordinary ginning roll box, 11 the huller 85 roll box, 12 the huller ribs, 13 the ginning ribs and 14 the saws of the saw cylinder. The saws are spaced apart by space blocks or spacers 15 which are of the usual construction now in common use. These parts 70 are of standard construction and are not elements of the invention.

Beneath the saw cylinder an air flue 16 extends longitudinally of the gin and is supplied with air under pressure in a suitable 75 manner. At its upper end the air flue is equipped with a nozzle 17 arranged in close relation to the teeth of the saws and preferably tangential thereto, so as to direct the air along said teeth in a clockwise direction, 80 in which direction said saws revolve.

The nozzle is contiguous to a relatively wide mouth 18 at the top of a lint flue 19 which extends down the front side of the air flue proper. The saws dip into this mouth 85 and the lint cotton is discharged directly into the same so that said lint is readily displaced into the lint flue. The term "air flue" may be used as designating the parts 16 to 19 inclusive, as a unit.

90 It is important that the mouth 18 be located in its entirety under the space blocks 15 and thus dirt or other extraneous matter, falling by gravity, cannot enter said mouth and enter the air flue. Further matter falling upon the space blocks will not be deflected into the mouth of the flue, but will be diverted therefrom. This arrangement makes for a cleaner staple.

95 By observing the drawing it will be seen that the saws will traverse nearly a half revolution from the point where the lint is drawn between the ribs to the mouth of the air flue. This increased distance or amplification over the usual practice, gives the 100 saws a greater opportunity and a longer period, in which to cast off the motes thru the agency of centrifugal force. Further by having the peripheries of the saws, 105 between the points above mentioned, free from 110

obstructions the motes cannot collect or interfere with the operation of the gin. The construction herein presented enables the saws to be run at a slower speed than is usually employed, thus giving a better opportunity for moting, and while the capacity of the gin may be slightly reduced, the gain in clean cotton more than compensates any such loss.

10 A conveyor 20 is arranged longitudinally of the gin in the bottom of a trough 21 and relatively below the space blocks. There is no obstruction at the upper end of the trough and the motes which are displaced from the 15 saws are cast directly into the trough. Any obstruction which would tend to collect motes or dirt in proximity to the saws, would be objectionable and would tend to soil the cotton.

20 In Fig. 2 I have shown a modified form in which a second cylinder of saws 14' is arranged above the usual cylinder and project into the top of the roll box 10. The saws are separated by space blocks 15, and directly under the same is the mouth 18' of an air flue comprising an air supply flue 16', a nozzle 17' and a lint flue 19'. A trough 21' is provided relatively below the space blocks 15' and has therein a conveyor 20'. The 25 upper saws have even a greater portion of their peripheries lying between the point where the lint is drawn between the ribs and the mouth of the flue. Moting will be very efficiently carried out by the upper saws 30 and the double saw construction will greatly enhance ginning.

This application is a division of my application filed March 13th, 1922, Serial Number 543,253 and all disclosures are included 40 herein.

While it is possible to operate the saws at a slower speed than is usually employed, it is to be understood that any desirable and practical speed may be used and the same 45 speeds which are now commonly used may be employed.

What I claim, is:

1. In an air blast cotton gin, a saw cylinder having circular saws and space blocks 50 between the saws, and an air flue having its mouth under the space blocks, whereby dirt and extraneous matter falling by gravity

are deflected from the mouth of the flue by said space blocks.

2. In an air blast cotton gin, a roll box, 55 ribs in the roll box, a saw cylinder having its saws passing between the ribs, an air flue having its mouth contiguous to the teeth of the saws and at a location remote from the point where the saws pull the lint between the ribs, a nozzle adjacent the mouth of the flue, and a lint flue contiguous to the mouth for receiving the lint deflected from the saws by the nozzle into the mouth, there being no obstructions or elements adjacent the peripheries of the saws between the points where the lint is drawn thru the ribs and the mouth of the flue.

3. In an air blast cotton gin, a roll box, 60 ribs in the roll box, a saw cylinder having its saws passing between the ribs, space blocks between the saws of the cylinder, an air flue having its mouth contiguous to the teeth of the saws and at a location remote from the point where the saws pull the lint between the ribs, a nozzle adjacent the mouth of the flue, a lint flue contiguous to the mouth for receiving the lint deflected from the saws by the nozzle into the mouth, and a mote conveyor located relatively below the 65 space blocks and removed from the saws.

4. In an air blast cotton gin, a roll box, 70 ribs in the roll box, a saw cylinder having its saws passing between the ribs, space blocks between the saws of the cylinder, and an air flue having its mouth directly under the space blocks of the cylinder and at a point located substantially one-half the circumference of the cylinder from the point where the lint passes thru the ribs.

5. In an air blast cotton gin, a roll box, 75 ribs at one side of the box, an upper saw cylinder, a lower saw cylinder, the saws of the cylinders projecting between the ribs into the upper and lower portions of the roll box, air flues having their mouths under the central portions of the cylinders, and nozzles adjacent the mouths of said flues for discharging the lint thereinto, whereby dirt and extraneous matter falling by gravity are deflected from the mouths of the flues.

In testimony whereof I affix my signature.

GEORGE E. EVANS.
